CROSS-FEED MECHANISM

Hans C. Weimar, Providence, R. I., assignor to
 Brown and Sharpe Manufacturing Company,
 Providence, R. I., a corporation of Rhode Island

Application January 14, 1947, Serial No. 722,002

13 Claims. (Cl. 51—165)

1

The present invention relates to an improved cross feed mechanism of the general type which is actuated by the reciprocatory movement of a work support to effect stepped cross feeding movements of a tool carrying cross slide against the work.

The invention is particularly illustrated and described as embodied in a grinding machine having a longitudinally movable work support, a headstock and footstock mounted on the work support, a grinding wheel, and a grinding wheel cross slide to which stepped feeding movements of predetermined extent are imparted at the end of the support travel in either or both directions. The operating and control devices for the machine include a table reversing lever shiftable to effect each reversal of table movement, and a pick cross feed for moving the grinding wheel relatively against the work including a cross feed ratchet, a pawl, and connections controlled by movement of the work support for actuating the pick feed to impart increments of feeding movement to the grinding wheel at the end of support travel in either direction.

It is a principal object of the invention to provide a novel and improved mechanism actuated by movement of the work support for operating the pick cross feed for the grinding wheel, which is simple in construction, accurate and certain in operation, and readily adjustable to cause an increment of advancing movement to be imparted to the grinding wheel at either or both limits of support travel.

With this and other objects in view as may hereinafter appear, a feature of the invention consists in the provision of a rotatable crank for effecting the feed and recovery strokes of the cross feed pawl, and connections from the reversing lever of the machine including means for adjustment of said connections so that for one position of adjustment, movement of the reversing lever from one to the other position will rotate the crank through an angle of approximately 360 degrees, and for an alternative position of adjustment is effective to rotate the crank through an angle of approximately 180 degrees. In the illustrated form of the invention, the connections for rotating the crank comprise a pair of toothed racks movable with the reversing lever, and a pair of pinions which are connected to rotate with the crank and are arranged to be selectively engaged with the racks. The driving connections including the racks and pinions engaging therewith are constructed and proportioned so that movement of the reversing lever from one to the other limit

2

is effective to rotate the crank through 180 degrees or 360 degrees depending upon the position of adjustment of the pinions.

Further in accordance with the invention, a locking and control device is provided which is adapted to insure that the rack and pinion connections are maintained at all times in the same phase relationship to one another. The device referred to, provides an interlocking connection which permits the pinions associated with the crank to be shifted from one to the other position of adjustment only for one predetermined angular position of the crank.

Further in accordance with the invention, the interlocking connection referred to is arranged to permit a ready adjustment of the pick cross feed to cause an increment of movement to be imparted to the grinding wheel selectively at one or the other limit of support travel as may be desired. In order to effect such adjustment of the pick cross feed, the pinions are first shifted to that position of adjustment in which movement of the reversing lever will cause the crank to be driven through an angle of 360 degrees. The reversing lever is then shifted to the position to which it would be moved by the table at that limit of travel at which the grinding wheel cross feed is to take place. The pinions are then again shifted to the alternative position of adjustment in which the crank will be rotated thereby through an angle of 180 degrees.

Further in accordance with the invention, the devices for effecting adjustment of the pick cross feed are so constructed and arranged, and the cover which normally encloses these devices, is so arranged with relation thereto to permit the cover to be moved to its closed position only when the pinions have been fully shifted to one or the other position of adjustment and are fully meshed with the corresponding racks.

The several features of the invention consist also in the devices, combinations and arrangement of parts hereinafter described and claimed, which together with the advantages to be obtained thereby will be readily understood by one skilled in the art from the following description taken in connection with the accompanying drawings, in which Fig. 1 is a view in front elevation of a grinding machine embodying in a preferred form the several features of the invention; Fig. 2 is a view in right side elevation with portions of the base sectioned to illustrate particularly the cross feed mechanism of the machine; Fig. 3 is an enlarged detail sectional view taken on the line 3—3 of Fig. 2; Fig. 4 is a view of sub-

stantially the parts shown in Fig. 3 looking from the right; and Fig. 5 is an enlarged sectional plan view taken on the line 5—5 of Fig. 1.

The invention is disclosed in a preferred form in the drawings as embodied in a grinding machine having a base 10, a work support 12 having mounted thereon a headstock 14 and tailstock 16 and adapted for translatory movement on ways 18, 20 on the base, a cross slide 22, and a grinding wheel 24. As shown in Figs. 1 and 2, the wheel 24 is mounted on a spindle 26 which is continuously driven from a motor 28 through a belt 30 which rides on pulleys, 32, 34 mounted respectively on the spindle 26 and on the armature shaft of motor 28.

The work support 12 is arranged to be power-operated by any conventional means as, for example, by the hydraulic mechanism shown in the patent to Maglott No. 2,163,246, issued June 20, 1939. The work support is under the control of a reversing lever 36 which is shiftable by means of reversing dogs 38, 40 from one to the other of two alternative running positions to effect reciprocation of the work support in the usual manner.

The mechanism for feeding the cross slide 22 and grinding wheel 24 toward the work, comprises a cross feed screw 42 supported at each end in bearings in the base 10, and having threaded thereto a nut 44 carried on a depending lug 46 on the cross slide 22. The feed screw 42 is connected through gears 48, 50 to a cross feed shaft 52 which carries at its outer end a micrometer cross feed ratchet 54. Stepped feeding movements are imparted to the ratchet and feed screw by means of a pawl 56 carried on a pawl supporting arm 58 pivotally supported intermediate its length on the shaft 52. At its outer end the arm 58 is connected by means of a vertically arranged link 60 to an adjustable crank arm in the form of a pivot pin 62 carried on a block 64 adjustably mounted in a radially disposed guide-way 66 in a crank disk 68. The crank disk 68 is secured to a rearwardly extending shaft 70 rotatably supported in anti-friction bearings 12, 74 in the base 10.

In accordance with a feature of the invention, novel connections are provided, rendered operative by movement of the reversing lever 36 from one to the other position to rotate the shaft 70 and crank mounted thereon to impart an intermittent stepped feeding movement to the cross feed mechanism. In accordance with the invention, the driving connections referred to, are constructed and arranged for adjustment to permit such stepped feeding movement to take place at either or both limits of travel of the work support. The actuating connections referred to, include an upwardly extending arm 76 which is supported to turn with the reversing lever 36, and is connected through a link 78 with an upwardly extending arm of an oscillatory actuating member 80 supported to turn on a stud 82 carried by a bracket 84 on the machine base. The actuating member 80 is formed at its lower end with two toothed segmental racks 86, 88 which are arranged for selective engagement respectively with pinions 90, 92 supported as a unit to turn with and to slide axially upon the shaft 70. The parts including the segmental racks 86, 88 and pinions 90, 92 are so proportioned and arranged that movement of the reversing lever 36 from one to the other running position will act through rack 86 and pinion 90 to turn the crank disk 68 through approximately 180 degrees rotation, and

will act alternatively through segmental rack 88 and pinion 92 to turn the crank disk 68 through approximately 360 degrees of rotation.

Adjustment of the actuating mechanism above set forth, to obtain a stepped feed of the cross slide at either or both limits of work support movement in accordance with the invention, is obtained by adjustment of the pinions 90, 92 in the following manner. In order to effect a cross feeding movement at both limits of movement of the work support, the pinions 90, 92 are shifted to their forward position so that pinion 92 is engaged with the segmental rack 88. The pinion 92 and rack 88 are so proportioned that each successive movement of the reversing lever 36 from one to the other operating position, will cause the crank disk 68 to be driven through an approximate revolution to retract and thereafter to advance the pawl 56. The sequence of the feed and recovery motions of the pawl 56 at the reversal of the table depends upon the position of the crank pin 62 relative to the notch in the crank plate 68 and the center of the plate. It is preferred that the recovery stroke precede the feed stroke in accordance with the illustration of Figs. 1 and 3. With the alternative arrangement, a less desirable condition is set up in which the grinding wheel plunge cuts a substantial distance from the end of the work and then "cuts air" for part of the return stroke.

In order to effect a stepped feeding movement of the cross feed at one limit only of the work support movement, the pinions 90, 92 are shifted rearwardly so that the pinion 90 is engaged with the segmental rack 86, these parts being so proportioned that movement of the reversing lever 36 from one to the other position will rotate the crank through 180 degrees only, causing the pawl to be moved either upwardly or downwardly to the opposite limit of its movement. For the position specifically illustrated in the drawings, in which the crank pin 62 is at the top limit of its movement, and the reversing lever 36 is to the right, it will be evident that movement of the reversing lever 36 to the left from the position shown in Fig. 1, as the work support 12 reaches the left hand limit of its travel, will cause the crank to turn through 180 degrees to move the pawl 56 upwardly to the top of its movement where it is held in stop position. The effect of this motion is to reset the pawl at the left hand limit of the work support movement. Return movement of the reversing lever at the opposite or right hand limit of table travel will then have the effect of rotating the crank 180 degrees in the opposite direction to its initial position to advance the pawl 56 downwardly, and to correspondingly advance the cross feed slide.

In the event that it is desired to set up the cross feed mechanism in such a manner as to cause the stepped feeding movement to take place only at the left hand limit of work support travel, the pinions 90, 92 are shifted forwardly when the crank pin 62 is in its extreme high position to engage the pinion 92 with the segmental rack 88. The reversing lever 36 is now shifted leftwardly to the opposite position from that shown in Fig. 1, causing the crank disk 68 and pin 62 to be carried through a full revolution to its initial position. The pinions 90, 92 may now be shifted rearwardly to engage the pinion 90 with the segmental rack 86. With the parts in this position, it will be evident that a shifting movement of the reversing lever from right to left as the work support reaches the left hand

limit of its movement, will have the effect of feeding the cross feed pawl 56 and cross feed slide while the reverse movement of the lever at the right hand limit of support movement will have the effect of resetting the pawl.

The mechanism for shifting the gear unit comprising pinions 90, 92 comprises an axially movable plunger 94 supported for axial movement in a plunger receiving bore 95 formed in the bracket 84 on the base 10. The plunger 94 is provided at its rear end with a clutch shifting fork 96 which embraces the gear 90, and at its forward end with a knurled manual control head 98. A compression spring 100 coiled about the plunger 94 between a shoulder 102 within the plunger receiving bore 95 and a shoulder 104 formed between the head 98 and reduced stem portion of the plunger 94 tends to maintain the plunger and associated parts including the gears 90, 92 in their relatively advanced position in which the pinion 92 is engaged with the segmental rack 88. A positioned pin 106 secured to the shifting fork 96 and arranged to slide within a bore in the bracket 84 serves to key the plunger 94 and shifting fork 96 against rotational movement.

Further in accordance with the invention, means are provided for controlling the operation of the cross feed adjusting means above described, including the pinions 90, 92 to maintain the correct operating relationship between the reversing lever 36 and the crank driven cross feed pawl 56. It will be evident that this operating relationship will be maintained only if the shift of the pinions 90, 92 from one to the other position takes place when the crank is in the same identical position each time the shift is made. In the illustrated form of the invention, the shift is made when the crank pin 62 is in the extreme up position. The mechanism for retaining the correct operating relationship of these parts, comprises an outwardly extending flange 110 formed on the rear peripheral edge of the crank disk 68. The flange 110 is arranged for engagement with either one of two notches 112 and 114 formed in the periphery of the head 98 of the plunger 94. The operative engagement of flange 110 with either of the notches 112, 114 serves to lock the plunger in the corresponding adjusted position. The flange 110 is formed with an arcuate cut-out 116 which for the extreme upward position of the crank pin 62, is in alignment with the plunger 94 to permit movement of the plunger from one to the other position. Further, the relationship of the cut-out 116 to the knurled head 98 of the plunger is such that the crank cannot be moved from its extreme up position until after the plunger has been fully shifted and the active pinion fully meshed with its cooperating segmental rack on the actuating member 80, when the flange 110 will have been brought into alignment with the corresponding notch 112, 114 of the plunger. The plunger 94 is securely latched in each of its adapted positions by means of a spring-pressed detent pin 118 which is supported for axial movement in a lug 120 on the bracket 84, and is arranged for engagement with either of two alternative recesses 122, 124 in the knurled head 98 of the plunger. The detent pin 118 is provided at its outer end with an enlarged knurled head 126 for convenience of operation by the operator.

For the protection of the parts including the crank connection provided by disk 68, pin 62 and link 60, a shield or cover 128 is provided hinged at its lower edge to turn on lugs 130. The cover 75

is normally held in closed position by means of a spring-pressed detent plunger 132 which is mounted in a lug 134, and is adapted for engagement with a tapered recess 136 in the side of the cover 128.

As a further safety feature which may serve to indicate to the operator that the pinions 90, 92 have been fully shifted from one to the other position, and which will serve as a warning to him in the event that the shift has not been completed, the locking plunger 118 including the knurled head 126 thereof, is so constructed and arranged with relation to the cover 128 as to permit the closing of the cover only when the plunger 118 has been fully seated in one of the recesses 122, 124.

It will be understood that the invention is not limited to the specific embodiment shown, and that various deviations may be made therefrom without departing from the spirit and scope of the appended claims.

What is claimed is:

1. In a machine tool having a work support adapted for translatory movement and a tool support adapted for cross feeding movement relatively to the work support, the combination of a cross feed mechanism for the tool support, which comprises a cross feed screw and nut, a cross feed ratchet and pawl, a crank connected to reciprocate the pawl, reversing dogs on the work support and a reversing lever actuated thereby, and means controlled by movement of the reversing lever for selectively moving the crank through approximate 180 degree and 360 degree angles of rotation, comprising a pair of toothed racks, and a connection from the reversing lever for imparting to-and-fro movement to said racks, and gear connections with the crank selectively connectible with said toothed racks.
2. In a machine tool having a work support and a tool support adapted for relative to-and-fro translatory movement and for relative cross feeding movement, and reversing means including a member shiftable from one to the other of two alternative positions with each reversal of said translatory movement, the combination of a pick cross feed mechanism comprising a cross feed ratchet, a pawl, a crank connected to impart a feed and recovery movement to the pawl for each full revolution of the crank, driving connections from said member constructed and having alternative positions of adjustment to rotate the crank approximately 180 degrees and alternatively to rotate the crank approximately 360 degrees with each shift of said member from one to the other position, and means for adjusting said driving connections.
3. In a machine tool having a work support and a tool support adapted for relative to-and-fro translatory movement and for relative cross feeding movement, reversing means including a member shiftable from one to the other of two alternative positions with each reversal of said translatory movement, the combination of a pick cross feed mechanism comprising a cross feed ratchet, a pawl, a crank connected to impart a feed and recovery movement to the pawl for each full revolution of the crank, and gear driving connections from said member for rotating the crank constructed and proportioned for alternative positions of adjustment of said connections to rotate the crank approximately 180 degrees and alternatively to rotate the crank approximately 360 degrees with each successive

shift of said member from one to the other position.

4. A pick cross feed mechanism for a machine tool having a work support and a tool support adapted for relative to-and-fro translatory movement and for relative cross feeding movement, and control means including a reversing lever shiftable from one to another of two alternative positions with each reversal of said translatory movement, which comprises a cross feed ratchet, a pawl, a crank connected to impart a feed and recovery movement to the pawl for each full revolution of the crank, gear connections from said member for rotating the crank including means for adjusting said connections whereby a shifting movement of the reversing lever from one to the other position is effective to drive the crank through one-half and alternatively through a full revolution.

5. A pick cross feed mechanism for a machine tool having a work support and a tool support adapted for relative to-and-fro translatory movement and for relative cross feeding movement, and control means including a reversing lever shiftable from one to another of two alternative positions with each reversal of said translatory movement, which comprises a cross feed ratchet, a pawl, a crank connected to impart a feed and recovery movement to the pawl for each full revolution of the crank, racking means arranged for oscillatory movement with said reversing lever, and a pair of rotary toothed members connected to the crank arranged for alternative engagement with the racking means, said racking means and rotary toothed members being proportioned and arranged to cause said toothed members to rotate the crank through 180 degree and 360 degree angles respectively.

6. A pick cross feed mechanism for a machine tool having a work support and a tool support adapted for relative to-and-fro translatory movement and for relative cross feeding movement, and control means including a reversing lever shiftable from one to another of two alternative positions with each reversal of said translatory movement, which comprises a cross feed ratchet, a pawl, a crank connected to impart a feed and recovery movement to the pawl for each full revolution of the crank, racking means arranged for oscillatory movement with said reversing lever, a pair of rotary toothed members connected to the crank arranged for alternative engagement with the racking means, said racking means and rotary toothed members being proportioned and arranged to cause said toothed members to rotate the crank through 180 degree and 360 degree angles respectively, and shifting means for shifting said rotary toothed members alternatively into operative engagement with said racking means.

7. In a machine tool having a work support adapted for to-and-fro translatory movement, a tool support adapted for transverse feeding movement relatively to the work support, and control means for the work support including a reversing lever shiftable from one to the other of two alternative positions with each reversal of the work support, the combination of a cross feed mechanism for the tool support, which comprises a cross feed screw and nut, a cross feed ratchet and pawl, a crank connected to reciprocate the pawl, a cross feed actuating member formed with two separate toothed racks connected for movement with the reversing lever, and a pair of pinions connected to rotate the

crank and axially shiftable for engagement selectively with said racks, whereby a shifting movement of the reversing lever from one to the other position is effective to rotate the crank alternatively through approximate 180 degree and 360 degree angles.

8. In a machine tool having a work support adapted for to-and-fro translatory movement, a tool support adapted for transverse feeding movement relatively to the work support, and control means for the work support including a reversing lever shiftable from one to the other of two alternative positions with each reversal of the work support, the combination of a cross feed mechanism for the tool support, which comprises a cross feed screw and nut, a cross feed ratchet and pawl, a crank connected to reciprocate the pawl, and actuating connections from the reversing lever for rotating the crank alternatively through approximate 180 degree and 360 degree angles for each shift of the reversing lever comprising an oscillatory crank actuating member having formed thereon two rack segments, a connection from the reversing lever for rocking said member, a pair of pinions connected to rotate the crank, and manual control means for relatively moving said pinions and member axially to engage the pinions alternatively with their respective racks.

9. In a machine tool having a work support and a tool support adapted for relative to-and-fro translatory movement and for relative cross feeding movement, reversing means including a member movable from one to the other of two alternative positions with each reversal of said translatory movement, the combination of a pick cross feed mechanism comprising a cross feed ratchet, a pawl, a crank connected to impart a feed and recovery movement to the pawl for each full revolution of the crank, driving connections from said member constructed and arranged and having alternative positions of adjustment to rotate the crank alternatively through approximate 180 degree and 360 degree angles with each movement of said member comprising a pair of toothed racks connected for movement with said member, a pair of pinions connected to rotate the crank, means to shift said pinions axially to engage the pinions selectively with their associated racks, and a locking device operable to permit axial movement of the pinions only for a predetermined angular position of the crank.

10. In a machine tool having a work support and a tool support adapted for relative to-and-fro translatory movement and for relative cross feeding movement, reversing means including a member movable from one to the other of two alternative positions with each reversal of said translatory movement, the combination of a pick cross feed mechanism comprising a cross feed ratchet, a pawl, a crank connected to impart a feed and recovery movement to the pawl for each full revolution of the crank, driving connections from said member comprising a pair of toothed racks connected for movement with said member, a pair of pinions keyed to turn with the crank and shiftable axially to engage the pinions alternatively with their associated racks, said connections including the racks and associated pinions being constructed and proportioned to rotate the crank alternatively through approximate 180 degree and 360 degree angles with each movement of said member, a shifting element for said pinions, and a locking connection between the crank and said shifting element arranged

normally to prevent movement of the shifting element and to permit such movement for one angular position only of the crank.

11. In a machine tool having a work support and a tool support adapted for relative to-and-fro translatory movement and for relative cross feeding movement, reversing means including a member movable from one to the other of two alternative positions with each reversal of said translatory movement, the combination of a pick cross feed mechanism comprising a cross feed ratchet, a pawl, a crank connected to impart a feed and recovery movement to the pawl for each full revolution of the crank, driving connections from said member comprising a pair of toothed racks connected for movement with said member, a pair of pinions keyed to turn with the crank and shiftable axially to engage the pinions alternatively with their associated racks, said connections including the racks and associated pinions being constructed and proportioned to rotate the crank alternatively through approximate 180 degrees and 360 degree angles with each movement of said member, a pinion shifting element movable axially of the crank, and a locking disk secured to turn with the crank, said shifting element having transverse slots to receive the peripheral edge of said disk for each position of adjustment of the pinions, and said disk having in the peripheral edge thereof a cutout to permit shifting of the shifting element for one angular position only of the disk.

12. In a machine tool having a work support and a tool support adapted for relative to-and-fro translatory movement and for relative cross feeding movement, and reversing means including a member movable from one to the other of two alternative positions with each reversal of said translatory movement, the combination of a pick cross feed mechanism comprising a cross feed ratchet, a pawl, a crank connected to impart a feed and recovery movement to the pawl for each full revolution of the crank, driving connections from said member constructed and ar-

ranged and having alternative positions of adjustment to rotate the crank alternatively through approximate 180 degree and 360 degree angles with each movement of said member, comprising 5 a pair of toothed driving elements connected for movement with said member, a pair of pinions connected to rotate the crank, a manually operable control for shifting said pinions to engage one or the other of the pinions with its associated rack, and a removable cover enclosing said manual control, said cover and manual control being constructed and arranged to permit the closing of the cover only for positions of the manual control corresponding with a fully shifted position of said pinions.

13. In a machine tool having a work support and a tool support adapted for relative to-and-fro translatory movement and for relative cross feeding movement, reversing means including a member movable from one to the other of two alternative positions with each reversal of said translatory movement, the combination of a pick cross feed mechanism comprising a cross feed ratchet, a pawl, a crank connected to impart a feed and recovery movement to the pawl for each full revolution of the crank, driving connections from said member constructed and arranged and having alternative positions of adjustment to rotate the crank alternatively through approximate 20 180 degree and 360 degree angles with each movement of said member comprising a pair of toothed racks movable with said member, a pair of pinions rotatable with the crank and shiftable axially for alternative engagement with said racks, 25 a manually operable shifting element for said pinions, a detent, and cooperating apertures in the shifting element within which the detent is seated for each position of adjustment of the pinions and shifting element, and a cover, said cover and detent being arranged to permit the closing of the cover only with the detent in seated 30 40 position.

HANS C. WEIMAR.
